UNITED STATES PATENT OFFICE.

THEOPHIL H. BERG, OF LINCOLN, NEBRASKA, ASSIGNOR OF ONE-HALF TO CHARLES R. WILKE, OF LINCOLN, NEBRASKA.

VOTING BOOTH.

Application filed November 7, 1927. Serial No. 231,614.

My invention relates to voting booths and one of its objects is the provision of a voting booth of simple construction and which may be easily set up or taken down by inexperienced laborers or others.

Another of my objects is the provision of parts which are standardized to a high degree, whereby the booth may be easily assembled and easily set up and whereby the 10 cost of manufacture and assembly is reduced to a minimum.

An important object of my invention is the provision of a booth which will comply with municipal and other regulations regarding 15 voting booths.

Having in view these objects and others which will be pointed out in the following description, I will now refer to the drawings, in which

20 Figure 1 is a view in perspective of a voting booth with one annex, parts of the canvas walls being torn away to disclose the frame structure of the two stall booth.

Figure 2 is a view in elevation showing one 25 of the walls of the booth in its folded position.

Figure 3 is a view in section through the upper extremities of two posts showing the braces.

30 Figure 4 is a view in section through the lower extremities of two adjacent posts at the rear of the booth.

Figure 5 is a perspective view showing the under side of the shelf.

35 The first unit of the voting booth is provided with rear and side walls which are similar to each other and with a front curtain. As shown in Figure 1, the end wall is provided with a front post 10 and with a rear post 11, the two posts being joined together by means of folding braces. The brace 12 extends diagonally from the lower portion of the post 10 to the upper portion of the post 11. It is secured to the post 10 by means of a

40 fixed clip 13 and to the post 11 by means of a slidable clip 14, the brace 12 being pivotally connected at its ends to the clips 13 and 14. Pivotally connected to the brace 12 is a cross-brace consisting of two parts 15 and 16 which are out of alignment with each other. The parts 15 and 16 are connected to each other and to the brace 12 by means of a Z-shaped connection. This connection consists of two metal Z-shaped straps 17 which are secured 45

50 on opposite sides of the parts 15 and 16 at

their ends so as to embrace the brace 12 to which they are pivotally secured. The part 15 is pivotally secured at its lower end to a clip 18 which is fixed to the post 11 on a level with the clips 13. The part 16 is pivotally secured to the clip 19 which is slidable on the post 10. The posts 10 and 11 are still further braced by means of the break joint brace consisting of the two parts 20 and 21, the outer extremities of which are pivotally connected 60 respectively to the posts 10 and 11. The inner extremities of the parts 20 and 21 are pivotally connected together and they are provided with a notch and pin arrangement for latching the parts 20 and 21 in their 65 straight line relation. The braces 12 and 16 are further provided with hooks 22 for engaging the parts 20 and 21 when in their extended relation.

70 In Figure 2 is shown the position of the 75 parts of the wall which they occupy in their folded relation. It is obvious that by pulling apart on the posts 10 and 11, the parts will assume the position as shown in Figure 1, the movement being stopped when the parts 20 and 21 are in their extended relation. It is also obvious that if the toggle connection between the parts 20 and 21 be broken, these parts will be released from the hook members 80 and the wall may be compressed by pushing together the posts 10 and 11 to fold the parts into the position shown in Figure 2.

85 The other side wall of the booth includes posts 23 and 24 and connections which are identical with those in the wall between the 90 posts 10 and 11. The rear wall is supported between the posts 11 and 24 and it is provided with a bracing system which is similar to that of the side walls. The braces 12' and 16' are identical with the braces 12 and 16 and they are pivotally attached to their respective 95 posts in the same manner. The rear wall, however, omits the brace 20-21 uniting the posts but it includes a two part brace 25 which is pivotally secured at its extremities to the braces 12' and 16'. The brace 25 has a toggle joint connection so that it may be broken to permit the posts 11 and 24 to be moved toward each other.

100 The unit of the voting booth as above described has canvas side and rear walls which are secured to the posts 10 and 23. In the folding of the booth the canvas may be folded so as to both form a compact bundle and to cushion the package. The front of the booth 110

is braced by means of a brace 26 which is pivotally connected at one of its ends to the upper extremity of the post 23 as shown in Figure 3 and which is provided at its opposite extremity with a loop for engaging the upper extremity of the post 10. In places where the regulations require a door or front wall for the booth, a canvas wall may be secured to the brace 26 to depend therefrom.

10 The annex is provided with only one side and a rear wall supported on three posts. The rear posts 27 and 28 are braced in the same way that the posts 11 and 24 are braced. The posts 28 and 29 are provided with the 15 same system of bracing used between the posts 10 and 11 or between the posts 23 and 24. The annex is positioned with the post 27 contiguous to the post 24, the connection shown in Figure 4 being employed to secure the 20 posts 24 and 27 in fixed position. The clip 30 is pivotally connected to the post 27 at its extremity and it is provided with a loop which may be passed over the extremity of the post 24. It will be noted in Figure 4 that the 25 posts 24 and 27 are slightly spaced to allow room for the clips 14 and 18. At their upper extremities the posts 29 and 23 are united and braced by means of a link similar to the link 26. The rear post 27 of the annex is also secured to the front post 23 of the booth by 30 means of a link 25^a which is pivotally secured to the post 27 and releasably latched to the post 23, the link being engaged by hooks projecting from the cross braces of the posts 23 and 24. In the annex the canvas is secured at its edges to the posts 27 and 29 to 35 form a back and one side wall.

Each stall of the voting booth is provided with a foldable shelf. As shown in Figure 40 5 this shelf consists of two like parts 31 and 32 which are hingedly connected together by means of the hinges 33. The free edge of the part 31 is adjacent the rear wall of the stall and the part 31 is provided at its lateral edges with engaging devices 34 for fastening the shelf to the brace members 21 on the opposite sides of the stall. At the forward corners of the part 32, engaging devices 35 are secured to the underside of the part 32 45 to project outwardly therefrom and with downturned ends whereby the shelf may be secured at its forward edge to the brace members 20. It should be noted that the width of the shelf member is such that they will fit 50 snugly within the stall of the booth so that when the engaging devices 34 and 35 are seated over the edges of the brace members 20 and 21, the shelf will be held very firmly in position. The brace members 20 and 21 are 55 each held firmly at three points so that they constitute a firm support for the shelf.

The voting booth as above described is of extreme simplicity in construction. It may be opened in a few seconds of time since near-

ly all of the linkage movements are automatic, it being only necessary to draw the posts apart and to latch them. When the booth is to be taken down, it is just as quickly folded and it then occupies a minimum amount of space so that it can readily be packed into a box of relatively small size. In the full size booth which I have constructed, the booth together with several annexes are packed in a box which is so constructed that it may be opened to form a table at which the election clerks may work.

The material used depends, of course, on circumstances. The posts may be made of wood or they may be made from sheet steel which has been bent into tubular form. For 80 the back and side walls as well as for the front curtain I prefer to use canvas but where the regulations necessitate an all fire proof construction the canvas may be impregnated with fire resisting substances or an asbestos curtain may be used in the place of the canvas.

Having thus described my invention in such full, clear, and exact terms that its construction and operation will be readily understood by others skilled in the art to which it pertains, what I claim as new and desire to secure by Letters Patent of the United States is:

1. A voting booth comprising four corner posts, crossed collapsible braces disposed between the posts at opposite sides and at the back of the booth and lying between the face planes of the sides and back, means for anchoring the lower ends of the braces to the lower ends of the posts, means for slidably connecting the upper ends of the braces to the upper portions of the posts, break-joint bars carried across the braces for holding the same extended when the booth is set up, and means for interlocking the crossing portions of the 105 braces and bars when extended.

2. A two compartment voting booth, comprising a main compartment having four corner posts providing a back and two sides, a second compartment having three corner posts providing a second back and a side, crossed collapsible braces disposed between the posts in said sides and backs, means for anchoring the lower ends of the braces to their respective posts, means for slidably connecting the upper ends of the braces to their respective posts, break-joint bars secured across the braces for holding the sides and backs extended when the booth is set up, means for interlocking the crossing portions of the braces and bars when extended, and means for detachably connecting the free corner post of the second back to one of the corner posts of the first back to utilize one side of the main compartment as a partition between the main and second compartments.

In testimony whereof I affix my signature.
THEOPHIL H. BERG.
